(57) **CLAIM**

The ornamental design for a modular entertainment system speaker, substantially as shown and described.

DESCRIPTION

FIG. 1 is a perspective view of a modular entertainment system speaker showing my design;

FIG. 2 is a front elevational view of FIG. 1, the rear, right side, and left side elevational views being mirror images thereof;

FIG. 3 is a top plan view of FIG. 1; and,

FIG. 4 is a bottom plan view of FIG. 1.
